ABSTRACT

A control valve has two valve pistons disposed on opposite sides of a straight passage which is connected at one end with an expanding and contracting pressure chamber of a hydraulic press or brake system, and has a discharge opening at the other end. The valve pistons have a first position in which fluid from the contracting pressure chamber can flow with minimal resistance through the straight passage and out of the discharge opening. In a second position of the valve pistons, the discharge opening is closed by the same, and pressure fluid can be supplied from an inlet through control valves into the straight passage and from there to the expanding pressure chamber.

CONTROL VALVE FOR THE FLOW TO AND FROM A VARIABLE PRESSURE CHAMBER

BACKGROUND OF THE INVENTION

Control valves which are particularly suitable for the operation of hydraulic presses, are known, in which valve pistons are arranged in a coaxial position and are movable toward and away from each other. The valve pistons have closure pieces provided with longitudinal and transverse bores, through which a pressure fluid is supplied to a consumer apparatus after several deflections. If this known control valve is shifted from the operative position to the inoperative position, the pressure fluid flows from the pressure chamber in the consumer apparatus through the control valve along a tortuous path on which it is several times deflected.

Due to the repeated deflection of the flows of fluid, delays occur during the shifting of the control valve between the two control positions in which fluid is supplied to, or discharged from the pressure chamber of the consumer apparatus.

Modern machines operate at very high frequencies of the strokes, which requires short shifting periods for the control valve, and shorter periods of time for filling and discharging the pressure chamber.

SUMMARY OF THE INVENTION

It is one object of the invention to provide a control valve which requires less time for shifting, and shorter filling and discharge periods than control valves of the prior art.

Another object of the invention is to provide a control valve which is automatically operative to stop the consumer apparatus when a malfunction takes place in the control valve.

Another object of the invention is to provide a control valve in which fluid flowing through encounters a minimum of resistance.

With these objects in view, the control valve according to the invention has a substantially straight passage between the opening leading to the pressure chamber of a consumer apparatus, and a return and discharge opening. In accordance with the invention, valve piston means are provided which close the discharge opening of the straight passage while fluid is supplied into the passage and through the same to the pressure chamber of the consumer apparatus.

Due to the straight connection between the return and discharge opening and the connection with the expandable and contractable pressure chamber of the consumer apparatus, such as a hydraulic pressure, very short filling and emptying periods are obtained, which is due to the fact that the direction of flow of the pressure fluid need not be changed, also due to the fact that the pressure fluid is not deflected during flow through a straight passage which is connected at one end with the pressure chamber of a hydraulic press, and has at the other end thereof a discharge opening. The housing has working cylinders laterally of the straight passage, and supply conduit means including an inlet conduit for supplying the pressure fluid into the working cylinders. Channel means connect the supply conduit means with the passage portions of the passage. Valve pistons are located in the working cylinders for movement toward and away from the straight passage between a first con-

trol position retracted from the straight passage so that fluid from the pressure chamber flows through the straight passage and directly out of the discharge opening, and a second control position located in the straight passage and closing the discharge opening.

The valve pistons are moved by pressure fluid in the supply conduit means and in the working cylinders to the second control position so that the discharge opening is closed, and pressure fluid flows through the channel means into the straight passage and out of the same into the pressure chamber of the consumer apparatus for expanding the same.

In the preferred embodiment of the invention, two oppositely arranged valve pistons have confronting inner frustoconical end portions cooperating with corresponding frustoconical valve seats. Each of the valve seats has a slot, and the slots are respectively closed by the two valve pistons in the second control position.

It is preferred to provide a channel in the valve pistons through which pressure fluid is guided into the straight passage. A spring between the valve pistons urges the same apart to the first control position. It is advantageous to provide check valves in the channels of the valve pistons, so that the valve pistons close the discharge opening of the straight passage, before the check valves open and the pressure fluid can flow through the straight passage into the pressure chamber of the consumer apparatus.

When a very large volume is required, it is advantageous to provide a valve for directly connecting the fluid inlet conduit with the straight passage.

In a preferred embodiment of the invention, each valve piston has its outer peripheral surface, at least one channel recess which is directly connected with the inlet conduit for the pressure fluid, and through which the pressure fluid can flow into the straight passage when the valve pistons are placed in the second control position closing the discharge opening. In such an arrangement, even a very great volume of pressure chamber, does not require an additional direct connection by a valve between the fluid inlet conduit and the straight passage.

It is advantageous to make the diameters of the piston parts outwardly of the channel recesses greater than the diameter of the piston parts located inward of the channel recesses, so that the pistons are urged outwardly to the first control position opening the discharge opening.

A further feature of the invention is to provide a double piston in a pressure cylinder forming balancing chambers at the ends of the pressure cylinder which are connected by first ducts with supply conduits for the fluid, and by second ducts with the straight passage. In such an arrangement, the double piston is operated to move to one of its end positions and to actuate a stop motion switch for the consumer apparatus, if one of the control valves for controlling the flow of pressure fluid to the channels of the valve pistons does not properly function, or if one of the valve pistons is blocked.

The novel features which are considered as characteristic for the invention are set forth in particular in the appended claims. The invention itself, however, both as to its construction and its method of operation, together with additional objects and advantages thereof, will be best understood from the following

description of specific embodiments when read in connection with the accompanying drawing.

BRIEF DESCRIPTION OF THE DRAWING

FIG. 1 is a schematic sectional view illustrating a first embodiment of the invention in a first control position;

FIG. 2 is a fragmentary schematic sectional view taken on line II-II in FIG. 1;

FIG. 3 is a schematic sectional view illustrating the embodiment of FIG. 1 in a second control position;

FIG. 4 is a fragmentary schematic sectional view taken on line IV-IV in FIG. 3;

FIG. 5 is a schematic section illustrating the embodiment of FIG. 1 in undesired condition caused by a malfunction;

FIG. 6 is a fragmentary cross section taken on line VI-VI in FIG. 5;

FIG. 7 is a schematic section illustrating a modification of the embodiment of FIG. 6 in a first control position;

FIG. 8 is a schematic sectional view of the embodiment of FIG. 7 in a second control position;

FIG. 9 is a schematic sectional view illustrating another embodiment of the invention in a first control position;

FIG. 10 is a fragmentary cross sectional view taken on line X-X in FIG. 9;

FIG. 11 is a schematic sectional view of the embodiment of FIG. 9 in a second control position; and

FIG. 12 is a fragmentary sectional view taken on line XII-XII in FIG. 11.

DESCRIPTION OF THE PREFERRED EMBODIMENTS

Referring first to FIGS. 1 to 4, a control valve 10 has a housing 12 in which two valve pistons 14 and 16 are movably mounted in working cylinders 15 and 17. The two pistons 14 and 16 are coaxial, and movable toward and away from each other. The confronting inner end portions 18 and 20 of the two pistons 14 and 16 are frustoconical, and cooperate with corresponding frustoconical valve seats 22 and 24. The working cylinders 15 and 17 are connected at the inner ends thereof by a passage portion 25. Valve pistons 14 and 16 are sealed in working cylinders 15 and 17 by sealing rings 14a and 16a. Each of the pistons 14 and 16 has a central axially extending channel or bore 26,28, respectively see FIG. 2, to which pressure fluid is supplied from supply channels 72 and 74 communicating through supply conduits 64 and 66 with an inlet conduit 62. A compression spring 30 is mounted in the aligned bores 26 and 28, and has outer ends abutting shoulders 32 and 34 provided in bores 26 and 28. Spring 30 urges the two valve pistons 14 and 16 apart. A check valve 36 and 38, respectively, is provided in each bore 26 and 28.

As shown in FIGS. 2 and 4, a passage 44 has an opening 40 at one end which is connected with the expanding and contracting pressure chamber of a hydraulic press, not shown, and has a discharge opening 42 at the other end thereof so that a pressure fluid discharged by the contracting pressure chamber of the hydraulic press can flow through passage 44 and out of discharge opening 42 without pressure loss. In accordance with the invention, the passage 44 between the openings 40

and 42 is straight so that fluid flowing into opening 40, through passage 44 and out of discharge opening 42, is not deflected, and consequently encounters very little flow resistance.

The straight passage 44 has two portions 45 and 47, of which the portion 45 is connected with the pressure chamber of the hydraulic press, and portion 47 is connected with the return conduit. The portion 45 is connected by a single opening 46 with the central space 49 from which a pressure fluid supplied through channels 26 and 28 can flow through portion 45 of passage 44 to the consumer apparatus, or through the discharge opening in portion 47 to the return conduit. The portion 47 of the straight passage 40 communicates with the central space 49 through two discharge slots 48 and 50 which are separated by a partition body 52, as best seen in FIGS. 2 and 4.

The discharge slots 48 and 50 have openings in the valve seats 22 and 24 of the valves 76 and 78, each of which includes one of the valve pistons 14 and 16, and the respective valve seats 22 and 24. The working chambers 77 and 79 of valves 76 and 78 are connected by supply conduits 72 and 74 with control valves 54 and 56 which have valve seats 58,68, and 60,70, respectively. The valve seats 58 and 60 of the two control valves 54 and 56 are connected by supply conduits 64 and 66 with the inlet conduit 62 to which pressure fluid is supplied in the direction of the arrow P. A pump, not shown, may be connected with the inlet conduit 62. The valve pistons 68 and 70 of the control valves 54 and 56 are, for example, electromagnetically operated. Control valve 56 controls valve 78, and control valve 54 controls valve 76. The control valve device 10 is provided with a stop motion arrangement for stopping the consumer apparatus, such as a hydraulic press, when a malfunction takes place. A pressure balancing device 80 is provided for this purpose, and includes a double piston 82 movable in a pressure cylinder 83 in housing 12. The end faces 84 and 86 of the double piston 82 form balancing chambers 85 and 87 which are connected by ducts 92 and 94 with the supply conduits 72 and 74 which connect the control valves 56,54 with the working chambers 77 and 79, and also connected by ducts 96 and 98 with the spaces 97 and 99 in front of valve pistons 14 and 16. As shown in FIGS. 1 and 3, ducts 96 and 98 open at the valve seats 22 and 24.

Check valves 100 and 102 are provided in the ducts 92 and 94, together with throttles 103 and 105. Double piston 82 has slanted actuating faces 104 and 106 which control the actuator of a stop motion switch 110.

The control valve device 10 shown in FIGS. 1 to 4 operates as follows:

In the position of FIG. 1, the two control valves 54 and 56 are closed, and pressure fluid cannot flow through conduits 62, 64, 66 and valve seats 58 and 60. Neither valves 76 and 78, nor the stop motion device 80 are subjected to fluid pressure. Double piston 82 is in a central position due to the action of springs 88 and 90. Stop motion switch 110 is open. Valve pistons 14 and 16 are in the retracted outer positions and the pressure chamber of the consumer apparatus, not shown, is connected with the opening 40 and through the straight passage 44 with the discharge opening 42, as shown in FIG. 2.

When the two control valves 54 and 56 are simultaneously actuated by electromagnetic means, they assume the position shown in FIG. 3, and the two relief openings 68 and 70 are closed, while the valve seat openings 58 and 60 are opened. The pressure fluid flows through supply conduits 62, 64 and 66, the valve seat openings 60 and 58, tee supply conduit portions 72 and 74 into the working chambers 79 and 77 of the valves 78 and 76. The outer end faces of valve pistons 14 and 16 are subjected to pressure of the pressure fluid so that the valve pistons 14 and 16 move inward towards each other. The spring biased check valves 36 and 38 in channels 26 and 28 of pistons 16 and 14 permit the building up of pressure in the working chambers 77 and 79 before opening the channels 26 and 28 for the flow of pressure fluid from the working chambers into the straight passage 44. The pistons 14 and 16 move towards each other until they abut on the valve seats 22 and 24, and close in this control position, the discharge slots 48 and 50 which communicate with the discharge opening 42 of the return conduit. The check valves 36 and 38 open so that the pressure fluid flows into the central space 49 and out of opening 46 into the end portion 45 of the straight passage 44 which is connected with the pressure chamber of the consumer apparatus.

The end faces 84 and 86 of the safety device 80 are subjected to equal pressure of the pressure fluid which flows through ducts 92 and 94. Ducts 96 and 98 which open in the valves seats are closed by the valve pistons 14 and 16 in the inner control position. Consequently, the double piston 82 remains in the central position so that stop motion switch 110 is not actuated.

FIGS. 5 and 6 illustrate a malfunction of the device. It is assumed that upon shifting of control valves 54 and 56 by electromagnetic means, only the control valve 54 opens, as control valve 56, perhaps due to failure of the electromagnetic means, has remained in the inoperative position closing opening 60.

Piston 14 is subjected to pressure and moves towards its valve seat, while piston 16 remains in the outer inoperative position. Discharge slot 50 is closed by piston 14, while discharge slot 48 remains open. The pressure fluid flows through control valve 54 and opening 58 into the working chamber 77 and through the respective check valve 38 and the corresponding channel 26 and the open discharge slot 48 directly to the return conduit. The ratio between the flow across sections of the control valves 54 and 56 and the channel 26 is about 1:10 so that in the interior of the valve, only a small pressure remains which is below the pressure required by the pressure chamber of the consumer apparatus, such as a coupling or a brake of a press. Consequently, no pressure fluid is supplied to the consumer apparatus.

Due to the one-sided pressure in the balancing chamber 85, which is not opposed by an equivalent pressure in the balancing chamber 87 due to the fact that the control valve 56 has not operated, double piston 82 moves to the left as viewed in FIG. 5 so that the slanted face 106 operates the actuator pin of the stop motion switch 110 which disconnects to a relay, not shown, the main switch of the press which is thus stopped.

The position of the control valve device shown in FIGS. 5 and 6 also results in the event that both control valves 54 and 56 are correctly operated, but valve piston 16 is blocked in this outer position. The pressure fluid flows through the channels in the valve pistons 14 and 16, and then flows through the open discharge slot 48 into the return conduit. The pressure fluid further flows through duct 92 and duct 94 towards the balancing chambers 87 and 85. While duct 96 is closed by valve piston 14 so that pressure can develop in the balancing chamber 85, duct 98 is open since valve piston 16 has not moved forward to the inner control position. The fluid flowing through duct 94 consequently flows through duct 98 into the space 97 in front of valve piston 16, and out of discharge slot 48. No pressure can develop in balancing chamber 87 so that the double piston 82 moves to the left and operates the stop motion switch 10.

The same condition of the device is obtained when the control valves 54 and 56 are shifted out of the position shown in FIG. 3 to the position of FIG. 1, while valve piston 14 is blocked in the inner control position shown in FIG. 5. Valve piston 16 is moved to the outer control position by the action of spring 30, so that discharge slot 48 leading to the return conduit, and also the opening of the duct 98 which is connected with balancing chamber 87 is uncovered. The pressure chamber of the consumer apparatus is relieved since the straight passage 44 to the discharge opening 42 is opened. In the same manner, the balancing chamber 87 is relieved since the pressure fluid flows away through duct 98. It is not possible for the pressure fluid to flow out of the balancing chamber 85, since the check valve 100 prevents relief through the control valves 54, 56, and duct 96 is closed by the blocked valve piston 14. The end face 84 of the double piston 82 is subjected to fluid pressure, while the end face 86 is relieved. Due to the pressure differential, the double piston 82 moves out of the central position as shown in FIG. 3 to the left, so that stop motion switch 110 is operated.

Preferably, throttles 103 and 105 are provided in ducts 92 and 94 in order to equalize small motion and shifting tolerances of the valves, and also for obtaining a uniform pressure built up in the safety device 80. For the same reason, double piston 82 may be provided with a throttle connecting the two end faces.

A modified embodiment of the invention illustrated in FIGS. 7 and 8 corresponds to the embodiments of FIGS. 1 to 6, but has a different channel arrangement for connecting the inlet conduit 82 with the straight passage 44.

For large volumes, the flow cross section of the control valves 54, 56 is insufficient for a large pressure chamber of the brake or clutch of the consumer apparatus, and therefore a large valve means 120 with a larger cross section is provided in housing 12, and is operated by an actuating piston 124. Valve 120 is connected by a channel 122 with the inlet conduit 62. The auxiliary piston 124 is connected by a piston rod 125 with valve 120, and is controlled by control valve 54 through a channel 126. In the open position of valve 120 shown in FIG. 8, pressure fluid from inlet conduit 62 flows through valve seat 128 and a connecting channel 130 directly into the portion 45 of the straight passage 44 which is connected with the consumer ap-

paratus, as explained with reference to FIG. 2. Due to the direct connection between the inlet conduit 62 and the straight passage 44, it is not necessary to supply fluid through supply conduits 72 and 74 and channels 26,28 in pistons 14 and 16, as described with reference to FIGS. 1 and 2. Instead of the channels 26 and 28, corresponding blind bores are provided in pistons 14 and 16 in which spring 30 is located for urging the pistons away from each other.

In the event that the valve 120 malfunctions and, for example, remains in the closed position as shown in FIG. 7, no fluid is supplied to the consumer apparatus. In the event that the valve 120 remains in its open position after the control valves 54 and 56 have been shifted, perhaps due to jamming of piston 124, the supplied pressure fluid flows through the discharge slots 48 and 50 which are opened by the retracted pistons 14 and 16. Consequently, a single valve 120 is sufficient.

In the embodiment illustrated in FIGS. 9 to 12, each of the two valve pistons 14' and 16' has four channel recesses 140 and 142, respectively, which extend parallel to the axis of symmetry of the respective piston and over a part of its axial length. The channel recesses 140 and 142, respectively, are spaced 90° in circumferential direction, and the bottom of the channel recesses 140,142 is preferably part-circular so that the channel recesses 140,142 are substantially segment shaped, as shown in the drawing.

The channel recesses form part of the channel means by which the inlet conduit 62 is connected with the straight passage 44 when the valve piston 14' and 16' are in the inner control position shown in FIG. 12. The channel recesses, and associated channels, replace the channel bores 26 and 28 of the embodiment of FIGS. 1 to 4.

In the position of the control valve device 10' shown in FIGS. 9 and 10, the control valves 54 and 56 are closed. The channel recesses 140 and 142 register with openings 160 and 162 and annular channels 161,163 in housing 12, and are further connected by supply conduits 64 and 66 with an inlet conduit 62 through which the pressure fluid is supplied. Sealing means 156 and 158 in housing 12 prevent in the position of FIG. 9, the flow of pressure fluid from channel recesses 140,142 into the straight passage 44. Sealing means 156 and 158 cooperate with portions 148 and 150 of the valve pistons 14' and 16'. Sealing means 152,154 seal the channel recesses 140,142 from the separate conduits 72 and 74 which are supplied with fluid when the control valves 54 and 56 are operated. Sealing rings 152,154 are mounted in annular portions 144 and 146 of the valve pistons 14' and 16'.

When the control valves 54 and 56 are moved to the position of FIG. 11, pressure fluid flows through valve seats 60 and 58 into the supply conduits 72 and 74 and exerts pressure on the outer end faces of valve pistons 14' and 16' so that the valve pistons move to the inner control position closing the discharge slots 48 and 50 which communicate with the discharge opening 42.

The channel recesses 140,142 are in this control position not any more sealed from the straight passage 44. The pressure fluid flows through inlet conduit 62, supply conduit 64 and 66, openings 160 and 162, and annular channels 161 and 163 into the channel recess 140,142 and out of the same through annular gaps

164,166, see FIG. 12, so that the fluid enters the straight passage 44 and flows to the consumer apparatus. Annular channels 168,170, see FIG. 12, are provided in housing 12 through which the pressure fluid flowing out of annular gaps 164 and 166 is guided to the opening 40 communicating with consumer apparatus.

As is apparent from the drawing, the diameter of the piston portions 154,156 which are located outwardly of the channel recesses 140,142 is greater than the diameter of the portions 148,150 which are located inwardly of the channel recesses 140,142. In this manner, a pressure differential is obtained which urges the valve pistons 14' and 16' out of the control position shown in FIG. 9. The embodiments of FIGS. 9 to 12 is particularly advantageous since it is suitable for very high volumes of the pressure chamber of the consumer apparatus without requiring valve 120 of the embodiment of FIGS. 7 and 8.

The spring by which the fluid is pressed out of the working chambers of valve pistons 14 and 16' in the embodiments of FIGS. 1 to 8, can be so designed that it permits a closing of the straight passage 40 by the valve pistons only at a predetermined pressure, for example more than 3 k/cm². Such an arrangement eliminates the necessity of providing a pressure operated switch responsive to the pressure of the fluid.

More than one safety device 80 may be provided for operating other switches when a malfunction takes place. It is advantageous to make the valve pistons of a synthetic plastic material so that the mass is small, permitting a further reduction of the time periods for acceleration of the pistons so that the time required for shifting the control valve device is further reduced.

It will be understood that each of the elements described above, or two or more together, may also find a useful application in other types of control valve devices differing from the types described above.

While the invention has been illustrated and described as embodied in a control valve device including a straight passage for connecting the variable pressure chamber of a consumer apparatus with a discharge opening, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptions should and are intended to be comprehended within the meaning and range of equivalence of the following claims.

What is claimed as new and desired to be protected by Letters Patent is set forth in the appended claims.

We claim:

1. Control valve for controlling the flow to and from a variable pressure chamber of a consumer apparatus, comprising housing means including a substantially straight passage means connected at one end with said pressure chamber, and having at the other end thereof a discharge opening, said housing means having working cylinder means laterally of said straight passage

means, and supply conduit means including an inlet conduit for supplying a pressure fluid into said working cylinder means; channel means connecting said supply conduit means with a passage portion of said passage means; and valve piston means located in said working cylinder means for movement toward and away from said straight passage means between a first control position retracted from said straight passage means so that fluid from said pressure chamber flows through said straight passage means and directly out of said discharge opening, and a second control position located in said straight passage means and closing said discharge opening, said valve piston means being moved by pressure fluid in said supply conduit means and in said working cylinder means to said second control position so that said discharge opening is closed, and pressure fluid flows through said channel means into said passage portion and out of said one end into said pressure chamber for expanding the same.

2. Control valve as claimed in claim 1, wherein said working cylinder means includes two working cylinders located on opposite sides of said straight passage means; wherein said valve piston means include two valve pistons located in said working cylinders; wherein said supply conduit means includes two supply conduits respectively connecting said inlet conduit with said working cylinder; wherein said channel means includes two channels formed by said valve pistons, respectively, and communicating with said working cylinders, respectively; and wherein fluid pressure in said supply conduits and working cylinders simultaneously urges said valve pistons to said second control position for together closing said discharge opening while pressure fluid flows through said channels and straight passage means into said pressure chamber.

3. Control valve as claimed in claim 2, wherein said working cylinders form frustoconical valve seats adjacent said straight passage means; and wherein said valve pistons have inner confronting frustoconical end portions abutting said frustoconical valve seats in said second control position.

4. Control valve as claimed in claim 3, wherein said straight passage means includes a partition body dividing said discharge opening into two discharge slots; wherein said frustoconical end portions of said valve piston in said second control position abut said partition body and close said discharge slots.

5. Control valve as claimed in claim 4, wherein said working cylinders are located outward of said valve pistons and receive the end portions of said valve pistons remote from said frustoconical end portions.

6. Control valve as claimed in claim 4, wherein said frustoconical end portions have central end faces spaced from each other in said second control position and located in said passage portion; and wherein said channels extend axially of said frustoconical end portions in said valve pistons and open on said end faces for connecting said supply conduits with said passage portion.

7. Control valve as claimed in claim 2 wherein said channel means include axially extending bores in said valve pistons having partly closed outer ends; and a pressure spring located in said bores between said partly closed ends, and urging said valve pistons apart to said first control position.

8. Control valve as claimed in claim 2, wherein said channels extend between the outer and inner ends of said valve pistons, respectively; and comprising biased check valves located in said channels, respectively, and adapted to close said channels so that said valve pistons are moved to said second control position by the pressure in said working cylinders whereupon the pressure increases in said working chambers and opens said check valves to permit flow through said channels into said passage means and out of said one end of the same.

9. Control valve as claimed in claim 2, comprising two control valves mounted in said housing means operable between an operative position opening said supply conduits, respectively, and an inoperative position closing the same so that the movements of said valve pistons are controlled by said control valves; and wherein the ratio between the effective flow cross sections of said supply conduits controlled by said control pistons and said channels in said valve pistons is about 1:10.

10. Control valve as claimed in claim 1, comprising a valve means located in said channel means and having a closed position, and an open position for connecting said inlet conduit directly with said straight passage means.

11. Control valve as claimed in claim 10, comprising control valve means mounted on said housing means operable between an operative position connecting said inlet conduit with said working cylinder means, and an inoperative position disconnecting the same; and comprising actuating piston and cylinder means for operating said valve means under the control of said control valve means.

12. Control valve means as claimed in claim 1, wherein said working cylinder means include two working cylinders located on opposite sides of said straight passage means; wherein said valve piston means include two valve pistons located in said working cylinders, respectively; wherein said supply conduit means include two supply conduits connecting said inlet conduit with said working cylinders, respectively; and wherein said channel means include channel recesses in said valve pistons communicating with said inlet conduit and being closed in said first control position, and communicating also with said straight passage means in said second control position.

13. Control valve as claimed in claim 12, wherein said valve pistons comprise sealing rings engaging said working cylinders in said first control position for sealing said channel recesses against communication with said straight passage means.

14. Control valve as claimed in claim 12, wherein channel recesses include a plurality of channel recesses spaced circumferentially about each of said valve pistons.

15. Control valve as claimed in claim 14, wherein said channel recesses extend in the respective valve piston parallel to the axis of symmetry of the same and over a part of the length of the same.

16. Control valve as claimed in claim 12, wherein each of said channel recesses has a part-circular bottom and is segment shaped.

17. Control valve as claimed in claim 12, wherein each valve piston has a greater diameter at the outer end portion remote from said straight passage means

than at the inner end portion thereof; and wherein said channel recesses are located between said inner and outer end portions.

18. Control valve as claimed in claim 1, wherein said working cylinder means include two working cylinders located on opposite sides of said straight passage means; wherein said valve piston means include two valve pistons located in said working cylinders, respectively; wherein said supply conduit means include two supply conduits connecting said inlet conduit with said working cylinders, respectively; wherein said housing means forms a pressure cylinder having ends; comprising a double piston in said pressure cylinder forming balancing chambers at said ends of said pressure cylinder and being movable between a central inoperative position, and two end positions; a stop motion switch actuated by said double piston in said end positions; wherein said housing means has first ducts connecting said supply conduits with said balancing chambers, respectively, and second ducts connected with said balancing chambers, respectively, and communicating with said straight passage means in said first control positions of said valve pistons, and being closed, respectively, by the respective valve piston in said second control position of the same whereby malfunctions of any valve piston causes movement of said double piston to one end position and actuation of said stop motion switch.

19. Control valve as claimed in claim 18, wherein

said valve pistons have confronting inner ends; wherein said housing means include valve seats for said inner ends engaged by the same in said second control position; and wherein said second ducts open in said valve seats, respectively, and are closed by the respective valve piston in said second control position of the same.

20. Control valve as claimed in claim 18, comprising check valves in said first ducts for blocking flow from said balancing chambers into said supply conduits, respectively.

21. Control valve as claimed in claim 18, comprising throttle means in said first ducts, respectively.

22. Control valve as claimed in claim 1 wherein said housing means has a top portion in which said one end of said straight passage means forms an opening communicating with said variable pressure chamber, and a bottom portion in which the other end of said straight passage means forms said discharge opening; wherein said valve piston means are movable in a direction transverse to said straight passage means; and wherein said supply conduit means are located in a plane transverse to said straight passage means; and further comprising control valve means mounted in said housing means operable for opening and closing said supply conduit means so that the movements of said valve piston means are controlled by said control valve means.
